William S. Gluck

ATTORNEY

UNITED STATES PATENT OFFICE.

ARTHUR H. LEVINE, OF NEW YORK, N. Y.

PROCESS FOR ORNAMENTING SURFACES.

Application filed September 2, 1921. Serial No. 497,938.

To all whom it may concern:

Be it known that I, ARTHUR H. LEVINE, a citizen of the United States, and a resident of 1354 Brook Avenue, in the county 5 of Bronx, city of New York, State of New York, have invented certain new and useful Improvements in Processes for Ornamenting Surfaces, of which the following is a specification.

10 Broadly considered, my present invention relates to the art of treating surfaces, and more particularly to the procedure for treating surfaces, and has special reference to the provision of an improved process for 15 the treatment of surfaces of celluloid or the like to produce ornamental effects thereon.

While my present invention has a wide range of usefulness, inasmuch as it finds a peculiar field of utility as an efficient process 20 for the production of surfaces ornamented by the deposition of a material or of materials thereon along predetermined designs or with predetermined outlines, I will proceed to describe my invention in connection 25 with the production of surfaces ornamented by deposition of matter thereon, it being understood, of course, that this is done merely as a matter of convenience as to those phases of my invention which have such broader 30 field of utility. In practice I have found that ornamenting surfaces by the deposition of a substance such as a coloring material, is attended with a number of difficulties, among which is that attendant upon the 35 fact that the coloring matter tends to run, resulting in a lack of clear outline as well as other deleterious effects, and that attendant upon the fact that the finer ornamental features, such as hair lines, are difficult to 40 produce by direct application by means of a tool such as a brush. These difficulties are particularly present where the surface to be ornamented is of celluloid.

Where in the following specification the 45 terms "colored" and "uncolored" are used, it will be understood that the former is intended to refer to the contrasting effect produced by treating a portion of the surface

with a substance which results in such contrast, and that the latter term refers to the 50 surface in its natural or unchanged state. Furthermore, where the term "coloring" matter is used in this specification, it is intended to refer to substances which, when applied to portions of a surface, produce a 55 contrasting effect thereon.

Where I have attempted to overcome the difficulties by the use of a "resist" before applying the coloring matter as hitherto practiced, I have found that where I painted 60 the surface with a "resist" about the outlines of the ornament to be formed, and then painted with the "resist" the finer hair lines within such outline, such hair lines could not be made sufficiently refined because, first, 65 of the well-known characteristic of "resists" which do not permit of satisfactory results in this particular, and furthermore, because the tool or brush that was necessarily used also made the desired effect impossible of 70 attainment. Where, on the other hand, I covered a portion of the surface with the "resist" and then removed sufficient of the "resist" to give the outline, leaving within the outline the hair lines to form the interior 75 ornamentation, I found that a large amount of "resist" was necessary, and this "resist" must ultimately be removed. This waste as well as the additional labor involved, made this method unsatisfactory. Furthermore, 80 both of the above methods produce the ornament in color with the surface thereabout uncolored, and this character of ornamentation is not the most desirable.

For the purpose of distinguishing between 85 ornamented portions of a surface which are of substantial dimensions in both length and width, with what are known as "hair line ornamentation," I have used the terms "gross" and "fine" throughout the specification and claims.

Among the more important objects of my invention are: The provision of a process for ornamenting surfaces by producing contrasting effects in which the sharp outlines 95 are secured both as to gross ornamentation

and as to finer hair lined ornamentation; the provision of a process for ornamenting surfaces which comprises the steps of producing the gross ornamentation by deposition of a "resist," and the finer lines by removal of a portion of the "resist" which has been deposited; and the provision generally of a new and improved process for ornamenting surfaces of materials such as celluloid.

10 The successive steps in my process have been illustrated in the drawings where

15 Fig. 1 shows a mirror ornamented by my process;

15 Figs. 2, 3, 4 and 5 show each step in the process used by me to produce a fragment of such ornamentation;

20 Fig. 6 shows a cross section through a portion of said ornamented surface; and

20 Figs. 7 and 8 illustrate two steps in the production of a border line.

25 In the drawings I have illustrated my invention as used to ornament the back of a mirror with a floral design for purposes of convenience only, and I will hereinafter describe my invention in connection with a fragment of this design, it being understood, of course, that what is said applies as a matter of fact to the production of the 30 whole ornamentation at one time.

30 Although my process involves generally the steps of coating with a resist and then treating the surface not coated to produce a contrasting effect, the particular way in 35 which these steps have been practiced, have been found by me to give the desired ornamental effect, with a minimum expenditure of effort and material.

40 Fig. 1 illustrates the first stage in my process which comprises the step of painting upon the surface 20 to be ornamented, with a "resist" such as asphaltum, the desired figure or design, of which an example is illustrated at 21 in Fig. 2, the design being solid with no interior ornamentation or 45 lines. A tool such as the brush shown at 22 may be used for this purpose. The "gross" outline shown in this figure can be efficiently produced in this manner.

50 In Fig. 3 I have illustrated the second stage of my procedure which is that of removing from this asphaltum coating, the portions thereof, with a sharp instrument, such as the knife shown at 23, these portions 55 24 corresponding to what are to be the finer hair line decorations appearing within the design. The asphaltum design thus produced is in effect the exact design aimed for.

60 I now apply to the surface which, if desired, can be bounded by border lines produced in a manner to be described herein-after, the material as shown at 25 in Fig. 4 which when deposited produces the de-

sired contrasting effect, such as a dye substance for example. This step in my process has been illustrated in Fig. 4, although as is obvious, it is not necessary to apply this substance to all of that portion of the surface covered by the asphaltum. As is obvious, this substance will be prevented from contact with the surface to be ornamented, wherever such surface is covered by the asphaltum. When the dye has become fixed, the "resist" is then removed in any desired or preferred manner, such as by the application of warm water, with the resulting ornamental floral design effect shown at in Fig. 5, the stippling 27 in this figure being intended to show the colored surface. Where the coloring matter used is a dye, the production of the design thereby as described above, will result in the raised effect brought out clearly in Fig. 6.

65 In Figs. 7 and 8 I have illustrated the 70 manner of producing a border line, the steps of which are generally the same as that used in effecting the design already described; as shown in Fig. 7, a broad line 31 is painted with asphaltum, within which the 75 fine border line is to be contained. With a sharp instrument such as that illustrated at 23 in Fig. 3, I remove the asphaltum to produce the sharp line shown at 32 in Fig. 8. The dye is then applied and the asphaltum removed as described previously to produce a very fine hair line border.

80 In using the above process in ornamenting celluloid surfaces, I have discovered that there is a tendency for the coloring substance to work through the asphaltum, with the obvious unsatisfactory results. To overcome this difficulty in the practice of my invention, which is caused in part at least by the undesired solubility of the asphaltum in 85 the presence of an aniline dye, I have found it desirable to use as a resist, a composition made up of asphaltum mixed with either beeswax or paraffine or both.

90 The term "resist" as used throughout this 95 specification is intended to refer to all such substances, which when applied to a portion of a surface prevents any substance from reaching or acting on such portion of the surface.

100 Having thus described my invention and 105 illustrated its use, what I claim as new and desire to secure by Letters Patent is the following:

1. In the art of ornamenting surfaces, the 110 process of producing the design by the use of a "resist" which comprises the steps of forming the gross design by deposition of the resist and forming the finer design portions by removing portions of the resist so 115 deposited.

2. In the art of ornamenting surfaces, the 120 process of producing the desired design by

the use of a resist which comprises the steps of forming the gross design with a resist and then removing portions of the resist to produce the finer portions of the design.

5 3. In the art of ornamenting surfaces, the process which includes the steps of forming the gross design with a resist, and of then

removing with a sharp instrument portions of the resist to correspond with the finer design portions.

In witness whereof, I have hereunder signed my name this 24th day of August, 1921.

ARTHUR H. LEVINE.
